178,347

COMBINED DECANTER AND STOPPER THEREFOR

Ernest L. Du Pree, Weston, Conn., assignor to Schenley
Industries, Inc., New York, N. Y., a corporation of
Delaware

Application December 7, 1955, Serial No. 39,196

Term of patent 14 years

(Cl. D58—6)

Fig. 1 is a front elevational view of a combined decanter and stopper therefor showing my new design;

Fig. 2 is a side elevational view thereof;

Fig. 3 is a top plan view thereof with the stopper removed;

Fig. 4 is a vertical sectional view thereof, as seen on the line 4-4 of Fig. 2;

Fig. 5 is a top plan view of the stopper portion thereof; and

Fig. 6 is a cross sectional view thereof, as seen on the line 6-6 of Fig. 1.

The side of the combined decanter and stopper therefor not shown, is the same as the side shown.

1 claim:

The ornamental design for a combined decanter and stopper therefor, as shown and described.
